UNITED STATES PATENT OFFICE.

HERBERT CLAUSER, OF ELKTON, MARYLAND, ASSIGNOR TO VICTORY SPARKLER & SPECIALTY COMPANY, OF ELKTON, MARYLAND, A CORPORATION OF DELAWARE.

TORPEDO.

Original application filed May 13, 1926, Serial No. 108,967. Divided and this application filed November 1, 1926. Serial No. 145,610.

This invention relates to toy torpedoes and more particularly to that type of toy torpedo commonly known as the tube torpedo.

It is a general object of the present invention to provide a novel and improved form of toy torpedo.

More particularly, it is an object of this invention to provide, in a tube torpedo, a casing having a pair of closures, one near each end, one of said closures being in the form of a cup having the walls thereof in engagement with the inner wall of the container and the other being a disc having its edge in engagement with the inner wall of the container, there being an explosive composition placed between the closures and a sealing compound in the ends of the container beyond the closures.

In this application, which is a division of the applicant's co-pending application Serial No. 108,967, filed May 13, 1926, there is disclosed a single exemplary embodiment of the invention.

In the drawing:

Fig. 1 is a longitudinal central section through a completed torpedo; and

Fig. 2 is an end view of the same.

In the manufacture of toy torpedoes, great economies must be effected in labor and materials owing to the extremely low retail price of the completed articles. Any arrangement of parts, which contributes to a reduction in the amount of labor, materially adds to the profit to be derived from the manufacture.

In the usual form of tube torpedo, some means must be provided for closing the ends of the tube. The process of manufacturing a torpedo comprises rolling the tube, cutting off a desired length, closing one end of the tube, filling with explosive composition and abrasive material, and closing the remaining end of the tube. Sometimes auxiliary coverings are placed over the tube and the ends to reinforce against the expanding gases.

The present applicant has found that simple end closures serving to temporarily retain the explosive and abrasive material are highly desirable since they can be later covered with a permanent sealing compound producing an extremely effective seal with a minimum of labor.

Referring to the drawing, it will be seen that the present invention makes use of a conventional tube 10 which may be formed of

paper, cardboard, or other suitable fibrous material, preferably by rolling from a sheet into a long tube and cutting into the proper lengths. A suitable adhesive to bind the convolutions of the tube may be employed, and, if desired, may incorporate certain water-proofing compounds. The ends 11 of the tube are preferably cut off at right angles to the axis thereof. The cross section of the tube may be circular, elliptical, or of any desired configuration.

The auxiliary bottom closure preferably takes the form of a cup 12 formed from a sheet of cardboard having the upturned edges or walls 13 formed, in a suitable punch press which may cut and form the cup in one or two operations. The cup is made of such a size that its walls 13 will snugly engage the inner wall of the tube 10 to insure a tight fit and an accurate and permanent positioning of the cup within the tube. The walls 13 contribute largely to this accurate and permanent positioning. If a plain disc were used the small area of contact of its edges with the tube wall would allow it to be readily displaced during loading. The use of a cup obviates the need of adhesive to secure the closure 12 in position. It has been found that the assembling of the tubes and cups may readily be accomplished by placing the cup on the end of a peg projecting from a flat surface a distance equivalent to the length of the tube minus the distance from the outer surface of the closure 12 to its end and forcing the tube over the peg and cup until its opposite end abuts the flat surface. This accurately positions the cup which retains its place even under the loading operation. The cup is initially shaped with flaring walls the resilience of which contributes to retain the cup in position.

After the cup is positioned, it is customary to assemble a group of the tubes in a tray and fill in the necessary explosive composition 14 and the gravel or other abrasive material 15.

A closure disc 16 is then applied over the gravel and spaced inwardly from its end of the tube a distance substantially equivalent to the spacing of the closure 12 from its end of the tube.

The portions of the tube ends beyond the closures 12 and 16 are next more or less completely filled with a suitable adhesive or seal-

ing compound 17 which may be put in position while in a liquid or plastic state and allowed to harden. The material preferred for this purpose is described in applicant's 5 co-pending application Serial No. 85,592, filed February 2, 1926. It is not found necessary or advisable to use a cup at the top end of the tube owing to the difficulty of assembly after the tube has been loaded and since there 10 is no tendency to move the upper end closure, it merely serving as a surface to prevent the plastic sealing compound from flowing down into the gravel and causing a large number of particles of the same to adhere to each 15 other with a deleterious effect on the exploding of the torpedo and the possibility of injuring persons when the explosion takes place.

Having thus described the invention, what 20 is claimed as new and desired to be secured by Letters Patent is:

1. In a toy torpedo, in combination, a tubular container having straight walls, a cupped closure arranged in one end of said container and frictionally engaging said walls, a disc closure arranged in the other end of said container, explosive composition included between said closures, said closures being spaced inwardly from the ends of said tube, and sealing means filling the ends of the 25 tube beyond said closures.

2. In a torpedo, in combination, a tubular container, a closure having resilient upturned edges engaging the inner wall of said container near one end, a disc closure within and near the other end of said container, explosive composition between said closures and sealing means filling the ends of the tube beyond 30 said closures to retain the same in position.

In testimony whereof I hereunto affix my 35 signature.

HERBERT CLAUSER
